UNITED STATES PATENT OFFICE.

CHARLES H. HOWLAND-SHEARMAN, OF INDIANAPOLIS, INDIANA.

MECHANICAL PULLER.

1,400,606.

Specification of Letters Patent. Patented Dec. 20, 1921.

Application filed October 21, 1920. Serial No. 418,456.

To all whom it may concern:

Be it known that I, CHARLES H. HOWLAND-SHEARMAN, a citizen of the United States, residing at Indianapolis, in the county of Marion and State of Indiana, have invented a certain new and useful Improvement in Mechanical Pullers, of which the following is a specification.

The purposes of my invention are as follows: first, to furnish a heavy duty mechanical puller, which shall be capable of generating as great a pull under manual effort as have the most powerful power-driven pullers previously in use requiring a much heavier equipment of gasoline or steam motors to operate the same; and second, to furnish a relatively light portable form of puller, which shall be entirely self-contained and capable of being permanently mounted upon a truck, so as to be conveniently drawn from place to place for its work in any outlying operations, such as pulling stumps, removing houses, replacing derailed rolling stock, etc.

I accomplish the objects indicated by means of the arrangements illustrated in the accompanying drawings of a portable example of my invention of the one thousand tons draft-capacity in which:

Figure 1 is a top plan view of my invention, with the upper frame-plate partially broken away from same, in order to reveal the general arrangements of the entire mechanism; Fig. 2 is a fragmentary transverse section, taken in the position of the line 2-2, Fig. 1, looking in the direction of the arrows, but showing secured thereon the upper frame-plate of which a part has been removed from Fig. 1 exhibiting in detail the bifurcated sleeve-nut housing and its contained sleeve-nut with the method of emplacement of the latter between the frame-plates of the machine; Fig. 3 is a fragmentary sectional view, taken in the position of the line 3-3 Fig. 1 looking in the direction of the arrows, but showing secured thereon the upper frame-plate partly removed from Fig. 1, and illustrating the details of the ratchet mechanism whose function is to transmit the power of the pressure linkage to actuate the sleeve-nut; Fig. 4 is a complete exterior top plan view of one of my mechanical pullers, drawn upon a reduced scale, but having the same construction as shown in Fig. 1; Fig. 5 is a fragmentary transverse sectional view, taken in the

position of the line 5-5 Fig. 1 looking in the direction of the arrows, but showing the upper frame-plate demounted from Fig. 1 replaced, in order to show the arrangement and method of pivoting the high pressure tractor-lever linkage between the upper and lower frame-plate; Fig. 6 is a fragmentary transverse sectional view taken in the position of the line 6-6, Fig. 1, looking in the direction of the arrows, but having replaced thereon the upper frame-plate shown as partially demounted from Fig. 1, exhibiting the connecting-members employed to transmit the energy from the low pressure linkage shown in Fig. 7, to the high pressure linkage shown in Fig. 5; and Fig. 7 is a fragmentary transverse sectional view taken in the position of the line 7-7, Fig. 1, looking in the direction of the arrows, but having secured thereon the upper frame-plate partly removed from Fig. 1, depicting the actuating lever and linkage part of the low pressure tractor-lever group, with one of the anchor loops and anchor bolts pivotally secured between the upper and lower frame-plates.

Similar numerals refer to similar parts throughout the several views.

Referring to Figs. 1, 4, and 5, 1 is the lower frame-plate of my mechanical puller, which frame-plate when the invention is supplied in its portable form may serve as a truck-bed superiorly secured upon the swivel-axle 2 provided with rubber-tired wheels 3 in front, and upon a fixed axle 4 provided with rubber-tired wheels 5 at the rear end thereof. It is obvious that both of said axles and sets of wheels may be dispensed with when the invention is furnished in the form of a fixed device, as when bolted to the platform of a locomotive crane, for wrecking purposes. The top of my invention is surmounted by the flat upper frame-plate 6 spaced equidistantly at all points from said lower frame-plate 1.

Referring particularly to Figs. 1 and 7, the push-bar 7 is adapted to fit in the socket 8 secured by the key 9 to the rock-shaft 10, turning in the upper roller-bearing 11 in the upper frame-plate 6 and the lower roller-bearing 12, in the lower frame-plate 1. Said rock-shaft 10 has intermediately secured thereon, the rock-lever 13 in the fork 14 of which is articulated by the pin 15 the power-link 16.

Referring to Figs. 1 and 7, the suspension

arm 17, of the primary suspension pin 19, having the lower reduction 20 passing through and secured to the lower frame-plate 1, by the nut 21, and the upper reduction 22 piercingly secured through the upper frame-plate 6, by the nut 23. The knuckle-pin 24 commonly articulates the inner end of said suspension-arm 17, the lower end of the power-link 16 and the outer end 10 of the delivery arm 25 of said primary tractor-levers 18, within the slot 26 of which said power-link 16 is received. The upper spacing sleeve 28 surrounding the primary suspension-pin 19, function to keep said 15 primary tractor-levers 18 centralized in the same plane with the rock-lever 15. As shown in Figs. 1 and 6, the inner end of said delivery arm 25 is articulated intermediately by the primary delivery-pin 29 to 20 the duplex connecting-lever 36, pivoted upon the fulcrum-pin 37. Said fulcrum-pin is provided with a lower reduction 38 piercing the lower frame-plate 1, and secured therein by the nut 39, and an upper reduction 25 piercing the upper frame-plate 6, and secured therein by the nut 41 so that said pin acts as a spacer between said frame-plates. The spacing-sleeve 42 surrounds said fulcrum-pin 37 and supports said duplex connecting-lever 36, the halves of 30 which are intermediately spaced by the collar 43 and the collar 44 acts as a spacer between the upper face of said connecting-lever and the frame-plate 6, the effect of 35 this arrangement being to centralize the connecting-lever in the same plane as that of the primary tractor-levers 18. A roller bearing 45 is provided in the inner end of the delivery arm 25, for the purpose of 40 minimizing friction in transmitting the intensified pressure therefrom to the connecting lever 36.

As indicated in Figs. 1, 5 and 6, the upper end of the connecting-lever 36 is articulated 45 by the connecting-pin 46 to the outer end of the connecting-link 47, and the inner end of said connecting-link is commonly jointed upon the knuckle-pin 48, forming the intermediate articulation between the duplex 50 suspension arm 49 sustained on the secondary suspension-pin 50 and the duplex delivery-arm 51 of the secondary tractor-levers 52. Said secondary suspension-pin 50 has the lower shouldered and threaded 55 reduction 53 piercingly secured through the lower frame-plate 1 by the nut 54, and an upper shouldered reduction 55 piercingly secured through the upper frame-plate 6 by the nut 56, so that said pin is adapted to act 60 as a spacing-strut, and a spacing-sleeve 109 on said pin is provided to separate the halves of said duplex suspension-arm 49.

While the central plane of effort of said duplex suspension-arm 49 is central to said 65 frame-plates 1 and 6 and therefore is coin-

cident with the plane of effort of the connecting-lever 36, the central plane of effort of the duplex delivery-arm 51, is sufficiently offset to re-align same with the common plane of effort of said connecting-lever 36 70 and of the primary tractor-levers 18 by means of an offset spacing-collar 57. This offset arrangement serves the double purpose of supporting the very great pressure developed by the secondary tractor-levers 75 52 immediately adjacent to the respective frame-plates, so as to avoid the possibility of spring of the suspension-pin 50 during operation, and also of enabling intermediate members to be spanned by the two halves of 80 the suspension-arm 49.

As indicated in Figs. 1 and 5, the upper end of said delivery-arm 51 is articulated by the secondary delivery-pin 58 articulated intermediately to the duplex delivery-beam 59, 85 sustained upon the delivery fulcrum-pin 60, secured between said frame-plates 1 and 6, having the lower threaded reduction 61 piercingly secured through the lower frame-plate 1 by the nut 62 and the upper threaded 90 reduction 63 secured through the upper frame-plate 6 by the nut 64. The fulcrum end of said duplex delivery-beam 59 is supported on the bolster 65, through which is piercingly secured said delivery fulcrum-pin 95 60. The two halves of said duplex delivery-beam 59 are cheeked exteriorly against the outer faces of the delivery-arm 51 of the secondary tractor-levers 52 which have between same the spacing-collar 66. 100

Referring to Figs. 1, 3, and 5, the forward end of said duplex delivery-beam 59 is articulated by the wrist-pin 67 to the duplex ratchet-link 68, which is jointed by the cross-head pin 69 to the cross-head 70, running in 105 the cross-head guide 71, secured by the cap-screws 72 to the upper frame-plate 6 and by the cap-screws 110 to the lower frame-plate 1, and the cross-head guide 73, secured by cap-screws as 74 to the lower frame-plate 1. 110

The pawl 75 is loosely mounted on the pawl-pin 76, but to enable said pawl to withstand the heavy stresses transmitted thereby, the butt thereof is firmly socketed within the cross-head 70. Said pawl is adapted to 115 engage the teeth of the annular ratchet 77, with which it is kept in contact by the compression-spring 78. When it is desired to release said pawl 75 from contact with said annular ratchet 77, the cam-lever 79 is rotated on its pin 80 connected to the outer end of the release-rod 81, jointed at its inner end to said pawl 75, by which rotation of said cam-lever 79 said compression spring 78 is compressed and said pawl is withdrawn from 120 engagement with the annular ratchet 77. Said annular ratchet 77 is coextensively formed upon the inner end of the tractor-screw sleeve-nut 82, which bears integrally thereon the draft-collar 83 journaled in the 125 130

- bifurcated sleeve-nut housing 84, 85, secured by through bolts 86 to the respective lower frame-plate 1, and upper frame-plate 6, as particularly indicated in Figs. 1 and 2.
- 5 Said tractor-screw sleeve-nut 82, bears an interior thread 87 adapted to engage therewithin the thread of the tractor-screw 88, bearing on its outer end the draw-head 89, provided with the draft-loop 90 for receiving cables or chains to be drawn by the puller. In the rear end of said tractor-screw 88 is firmly shrunk the square bar 91, fitting in the square hole 92 of the bracket 93 secured by cap-screws as 94 to the respective upper 10 and lower frame-plates 1 and 6, as indicated in Figs. 1 and 5. The purpose of said square bar is to permit free longitudinal motion of the tractor-screw 88 when acted upon by the tractor-sleeve nut 82, but to prevent rotation 15 of the same, as such rotation would twist the cables or chains being drawn thereby. Various modifications in the construction of the particular parts illustrated and above described as exemplifying my tractor-screw 20 sleeve-nut and ratchet mechanism, may be made without altering its essential function of converting the push of the delivery-beam 59 to the pull of the draw-head 89. For example, I may use an oil-immersed force-lubricated tractor-screw, with an oil-immersed roller thrust-bearing to relieve the sleeve-nut; or I may substitute a self-meshing rack 25 and pinion for the pawl and ratchet etc.
- Figs. 1, 3, and 4 give views of the quick-return mechanism by which the tractor-screw 88 is pushed rapidly outward from the mechanical puller after each tractive actuation thereof. This quick-return mechanism consists essentially of the crank 94, provided 30 with the crank-handle 95, keyed to the crank-shaft 96, journaled in the upper frame-plate 6, as particularly indicated in Fig. 3. The inner end of said crank-shaft 96 has keyed thereon the bevel pinion 97 which meshes 35 with the bevel gear 98, preferably made co-extensive on the inner end of the sleeve-nut 82 as shown in Fig. 1.
- Referring to Figs. 1, 4 and 7, the spacer-bolts 99, 100, are piercingly secured through 40 the upper frame-plate 6 and lower frame-plate 1 by nuts as 101, 102, and are made to perform the joint function of swivel-bearings for the respective anchor-loops 103, 104, and of assembling members for said frame-plates. Said anchor-loops are vertically 45 spaced by rest-collars as 105, and top bolsters as 106, in such manner that the centers of same shall aline in the same plane with the long axis of the tractor-screw 88, in order that the anchorage cables passing 50 through the anchor-eyes 107, 108, shall present a plane of resistance substantially identical to the plane of pull of said tractor-screw which is regarded as an important 55 practical feature of my invention, both for preventing internal strain in the mechanism and to avoid refreeing any of the vast efforts developed to its support such as the truck-wheels 3 and 5.
- The operation of my mechanical puller is 70 as follows: When the push-bar 7 is shoved toward the anchor-loop 103, the pressure passing from the rock-lever 13 through the power-link 16 bends the straightened primary set of tractor-levers 18, thus generating and transmitting a much augmented pulling effort from the latter through the connecting-lever 36, and connecting link 47 to the knuckle-pin 48 of the straightened secondary set of tractor-levers 52, thus 75 bending said straightened set of secondary tractor-levers 52, which are thus caused to generate a further intensified force, which is transmitted through the ratchet link 68 to the cross-head 70 and the pawl 75 pivoted 80 therein.
- The rectilinear thrust of said pawl 75, as the same engages with the annular ratchet 77 on the sleeve-nut 82, rotates the latter with great power and, in so doing, converts 85 the push of the entire mechanism delivered by the non-revolvable tractor-screw 88, as it is drawn inward continuously by every revolution of said tractor-nut 82, thus producing a steady and extremely powerful draft 90 on the draw-head 89, which, being resisted by the cables engaging the anchor-loops 103, 104, causes the draft-chains passing through the draft-loop 90, to be drawn toward the puller with great force. 100
- Having thus described my invention, I claim:
1. The combination in a mechanical puller of a tractor-lever mechanism, with a tractor-screw mechanism adapted to be actuated by said tractor-lever mechanism, substantially as described. 105
  2. Combined in a mechanical puller, a frame; a power mechanism pivoted to said frame, adapted to transfer externally applied power for actuation of said puller; a pressure-intensifying mechanism, pivoted in said frame, capable of rectilinearly delivering pushing pressure under the actuation of said power mechanism, and a converting mechanism actuatable by said pressure-intensifying mechanism, adapted to convert the pushing pressure thereof into an intensified tractive effort, substantially as described. 110
  3. Combined in a mechanical puller, a frame, adapted to be actuated by said pressure mechanism; a tractor-lever mechanism pivoted in said frame, the power mechanism pivoted to said frame; a tractor-screw mechanism, adapted to be actuated by said tractor-lever mechanism, compressing a pawl-and-ratchet mechanism adapted to convert the rectilinear thrust of said tractor-lever mechanism into a rectilinear pull by said 115

mechanical puller, substantially as described.

4. Combined in a mechanical puller, a frame; power members in said frame adapted to apply power to said mechanical puller; a tractor-lever mechanism pivoted in said frame, adapted to be actuated by said tractor-lever mechanism; a draw-head on said tractor-screw mechanism for delivering the 10 pull of said mechanical puller; and members in said frame adapted to securely anchor said puller when in operation, substantially as described.

5. Combined in a mechanical puller, a frame; power members comprising a push-bar and rock-lever pivoted in said frame; inter-connected dual sets of tractor-levers, adapted to be actuated by said power members; a delivery beam pivoted in said frame, 20 adapted to be actuated by said inter-connected dual sets of tractor-levers; a pawl-and-ratchet mechanism adapted to be actuated by said delivery beam; a revoluble interiorly-threaded sleeve-nut, longitudinally fixed in said frame, adapted to be actuated by said pawl-and-ratchet mechanism; and, 25 threadingly engaged within said revoluble sleeve-nut, a non-revoluble tractor-screw, adapted to be longitudinally actuated by said revoluble sleeve-nut, substantially as described.

6. Combined in a mechanical puller, a frame, comprising spaced parallel plates,

adapted to hold between the same the puller mechanism; power members comprising a 35 push-bar and rock-lever, pivoted to said frame; inter-connected dual sets of tractor-levers, adapted to be actuated by said power members; a delivery beam, pivoted in said frame, adapted to be actuated by said inter-connected dual sets of tractor-levers; a pawl-and-ratchet mechanism adapted to be actuated by said delivery beam; a revoluble, 40 interiorly-threaded sleeve-nut, longitudinally fixed in said frame, adapted to be actuated by said pawl-and-ratchet mechanism; a non-revoluble tractor-screw, threadingly engaged 45 within said revoluble sleeve-nut adapted to be longitudinally actuated by said revoluble sleeve-nut; a draw-head on said tractor-screw, adapted to deliver the draft of said mechanical puller; and a quick-return mechanism comprising a crank with a bevel pinion on said frame, engaging a bevel gear on said sleeve-nut, adapted to make quick 50 return of said tractor-screw after each draft actuation thereof, substantially as described.

In witness whereof, I have hereunto set my hand and seal at Indianapolis, Indiana, this 16th day of October, A. D. nineteen 55 hundred and twenty.
